A. C. SOULE

SASH HANGER

Filed Aug. 28, 1925

UNITED STATES PATENT OFFICE.

ARTHUR C. SOULE, OF SAN FRANCISCO, CALIFORNIA.

SASH HANGER.

Application filed August 28, 1925. Serial No. 52,980.

This invention relates particularly to a hanger for supporting and controlling the opening and closing movements of a sash or other analogous inclosure.

5 An object of the invention is to provide a sash that will be superior in point of simplicity, inexpensiveness of construction, positiveness of operation and facility and convenience in use and general efficiency.

10 A further object of the invention is to provide a hanger or hangers, for supporting a sash, or other analogous inclosure, within an enclosing frame, for controlling and regulating the opening and closing movements of the sash and having means thereon to regulate the friction of the moving parts of the sash hanger.

15 A still further object of the invention is to provide in combination with a window frame and sash, of means interposed between the said sash and frame to maintain the sash in any desired open or closed position against wind pressure and the like.

20 Other objects and advantages will appear 25 as this description progresses.

In this specification and the annexed drawings, the invention is illustrated in the form considered to be the best, but it is to be understood that the invention is not 30 limited to such form, because it may be embodied in other forms, and it is also to be understood that in and by the claims following the description, it is desired to cover the invention in whatsoever form it 35 may be embodied.

In the accompanying one sheet of drawings,

40 Fig. 1 represents a plan section through a window frame having a sash mounted therein on a sash hanger constructed in accordance with my invention.

45 Fig. 2 is an enlarged vertical section, in condensed form, taken through Fig. 1 on the line 2—2, showing the sash hanger interposed between the top and bottom edges of the window sash and supporting frame.

Fig. 3 is an enlarged plan view of one of the sash hangers.

50 Fig. 4 is an enlarged section taken through Fig. 3 on the line 4—4.

Fig. 5 is an enlarged fragmentary section taken through Fig. 3 on the line 5—5.

55 Fig. 6 is a modified form of sash hanger showing the guideway and bearing plate as a single unit.

This invention relates particularly to a sash hanger or other equivalent sash operating structure, that is adapted to be positioned at corresponding points on either the opposite sides or ends of a sash, for supporting and controlling the movements of the sash in all open, closed and reversed positions. I have illustrated a vertically positioned sash equipped with my sash hangers and adapted to open on a vertical plane, but it is understood that the type of sash hanger shown could be applied equally as well to a sash that is adapted to open on a horizontal plane. Likewise, it is to be clearly understood, as being within the contemplated scope of the invention, that the sash hanger will operate in a practical and efficient manner on all different types of metal windows and transoms, even though the present drawings show the sash hanger associated with a wooden structure.

In detail, the construction illustrated in the drawings includes a window frame composed of a sill 1, stool 2, and side jambs 3, connected across the top by a lintel 4, together with the usual stops 5, and the other weather proof finish, mounted on the interior and exterior of the jambs, sill and lintel. The window frame, as described, is constructed to receive, in a completely operative manner, the window sash 6. The window sash 6 is supported within the window frame by complementary sash hangers secured, respectively, to the top and bottom ends of the sash, and frame, when the sash is of the "casement type", or the sash hangers are interposed between the opposite sides of the sash and window frame, when the sash is of the "awning type". The sash hangers on which the sash is supported in the window frame, are complementary, and each are secured at corresponding points on opposite sides of the sash, whereby both of the hangers will be operated simultaneously and in unison. The sash hangers on the opposite sides of the sash or on the opposite ends of the sash, are identical in construction and in operation, the only difference being that each pair of sash hangers consists of one right hanger and one left hanger.

At corresponding points on opposite sides of the window frame, which in the present instance happens to be the sill 1 and lintel 4 of the frame, I have secured metal guideways 7, each of which have an upstanding

flanged edge 8 thereon. The guideways 7 are secured to the window frame by means of wood screws, or some other appropriate fastening means. Each guide way 7 is provided with a curve of substantial radius thereon, to form the flanged edge 8. Although I have described metal guideways 7 in particular, it is to be understood that corresponding opposite sides on the window frame could be grooved to provide guide ways that are the equivalent of the metal guideways.

The stops 5 are adapted to be secured to the interior of the window frame, so as to partially cover the sash hangers, and so as to finish the window frame in accordance with standard practice. The sash 6 is provided with pieces of weather stripping 9 and 10, on its opposite ends, and said weather stripping extends into suitable openings provided in the window frame finish so as to exclude and to prevent inclement weather from passing the sash when the said sash is in the closed position.

25 A slide shoe 11, consisting of a metal member with a U-shaped flanged end 12 is slidably retained on each of the guideways 7. The flanged end of the slide shoe is adapted to snugly fit the flanged edge 8 and curve 30 of the metal guideway 7, and to prevent any separation of the parts when in an operating position. The end 13 of the slide shoe, opposite the flanged end 12, is spaced upwardly and away from the face of the metal guideway 7 so as to leave a substantial space therebetween.

A sash plate 14 is pivoted at 15 to the projecting end 13 of the slide shoe 11. The sash plate 14 is provided with screw holes, 40 through which fastening screws may be passed for the purpose of securely anchoring the sash 6 onto the sash plate. As shown in Figs. 1 and 2, sash plates 14 are screwed onto the top and bottom edges of the sash 6. A control arm 16 has one end thereof pivoted at 17 to the under face of the sash plate 14 adjacent the end thereof, and the opposite end of the arm 16 is pivoted at 18 to a bearing plate 19 which abuts an end 45 of the guide way 7. Although I have shown the bearing plate 19 and guideway 7 to be separate parts, it is to be understood that it would be clearly within the purview of the invention to make said parts out of a single strip of material. The bearing plate 19 is provided with a raised central portion and down turned flanged ends 20 through which fastening screws are passed into the window frame. The bearing plate 19 is provided with an arcuate slot 21 therein, cut on a radius struck from the pivotal axis of the pivot 18 and fastening screw 22 is arranged in the arm 16 to pass through the slot 21 in the bearing plate 19.

65 A yieldable or resilient friction plate 23

that is slightly concave in form, has one end thereof secured to the under side of the arm pivot 18. The friction plate 23 is co-extensive with the arm 16 and the free end of the friction plate 23 is tapped to be engaged 70 by the threaded end of the adjusting screw 22. By tightening on the adjusting screw 22, the control arm 16 and friction plate 23 are drawn tightly against the opposite faces of the bearing plate 19, and frictionally 75 engaged therewith. As the adjusting screw 22 is unloosened, the curved friction plate 23 tends to draw away from the under face of the bearing plate 19 and to diminish the frictional resistance between the arm 16, 80 friction plate 23 and the bearing plate. The adjusting screw 22 functions as a regulatory medium, by means of which the friction on the control arm 16 may be increased or diminished so as to control the movement of 85 the sash hanger. The screw 22 controls the entire operation of the sash hanger, and is so characterized that a sash mounted on hangers constructed in accordance with my invention may be placed in any desired position without fear that wind pressure or the like will cause the position of the sash to be changed. A sash supported on my sash hangers does not require any auxiliary or additional mechanism for holding the sash 90 in a closed or opened or partly opened or reversed position.

The sash illustrated in the drawings, when operatively installed in a window frame, is opened best by manually pushing on that side of the sash opposite to which the sash hangers are secured. As the free end of the sash is moved, the opposite end of the sash causes the slide shoes to slide on the guideways, and the sash plates and supporting arms to swing outwardly into the opened position. The construction of the sash hanger is such that a sash mounted thereon, in the manner described, may be substantially reversed in a window mounting so as to 100 present its outward surface to the interior of the room, to facilitate washing.

The body of the slide shoe 11 extends at an angle to the U-shaped flanged end 2 thereof, as shown by the dotted lines in Fig. 5. The purpose of so making the slide shoe 11 is to cause the flanged end thereof to be forced into snug engagement with the guideway at the point indicated by the arrow, when the body of the slide shoe is forced by the sash out of its angular position, into a position substantially parallel with that part of the guideway screwed onto the window frame. The wedging of the sash between the angular ends of the slide shoes on opposite guide ways is compensated for by the U-shaped ends of the slide shoes tightly gripping the sash guide ways to furnish an effective friction.

Having thus described this invention, 130

what I now claim and desire to secure by Letters Patent is:

1. A sash hanger comprising a guide way having an arcuate slot therein; a shoe slidably mounted on said guide way; a sash plate having one end pivoted to said shoe; an arm pivoted at one end to said sash plate and pivoted at its other end to the guide way adjacent the arcuate slot; and means interposed between the guide way and arm, working in the arcuate slot, to control the turning movement of the arm.
  2. A sash hanger comprising a bearing plate; a guide member having an end thereof adjacent the bearing plate; a shoe slidably mounted on said guide member; a sash plate having one end thereof pivoted to said shoe; an arm pivoted at one end to said sash plate and pivoted at its other end to the bearing plate; and regulatory means independent of the arm pivot to hold the arm in frictional contact with the bearing plate.
  3. A sash hanger comprising a bearing plate having an arcuate slot therein; a guide member having an end thereof abutting the bearing plate; a shoe slidably mounted on said guide member; a sash plate having one end thereof pivoted to said shoe; an arm pivoted at one end to said sash plate and pivoted at its other end to the bearing plate; and an adjustable frictional member mounted in the arm in registry with the arcuate slot to control the arcuate movement of the arm.
  4. A sash hanger comprising a guide way; a shoe slidably mounted on the guide way; a sash plate having one end pivoted to said shoe; an arm pivoted at one end to said sash plate and pivoted at its other end to the guide way; and means movable with the arm to hold the arm in frictional contact with the guide way.
  5. A sash hanger comprising a bearing plate having an arcuate slot therein; a guide member having an end thereof abutting the bearing plate; a shoe slidably mounted on the guide member; a sash plate having one
- end pivoted to said shoe; an arm pivoted at one end to said sash plate and pivoted at its other end to the bearing plate; and adjustable means on the arm engaging the slot in the bearing plate to hold the arm in frictional contact with the bearing plate.
6. A sash hanger comprising a bearing plate having an arcuate slot therein; a guide member having an end thereof abutting the bearing plate; a shoe slidably mounted on the guide member; a sash plate having one end pivoted to said shoe; an arm pivoted at one end to said sash plate and pivoted at its other end to the bearing plate; a friction plate secured to the arm pivot on the underside of the bearing plate; and an adjusting screw in the arm projecting through the slot in the bearing plate into engagement with the friction plate to move the arm and friction plate relative to the opposite faces of the bearing plate.
7. A sash hanger comprising a bearing plate; a guide member; a shoe slidably mounted on the guide member; a sash plate having one end pivoted to said shoe; an arm pivoted at one end to said sash plate and pivoted at its other end to the bearing plate; and regulatory means secured to the arm pivot to hold the arm in frictional contact with the bearing plate.
8. A sash hanger comprising a bearing plate; a guide member; a shoe slidably mounted on the guide member; a sash plate having one end pivoted to said shoe; an arm pivoted at one end to said sash plate and pivoted at its other end to the bearing plate; a friction plate mounted around the arm pivot on the under side of the bearing plate; and adjustable means to vary the frictional relation of the friction plate and arm relative to the bearing plate.

In testimony whereof, I have hereunto set my hand at San Francisco, California, this 20th day of August, 1925.

ARTHUR C. SOULE.
